UNITED STATES PATENT OFFICE

2,585,081

COMBUSTION APPARATUS FOR LIQUID FUEL

George Bernhard, Hewlett, N. Y., assignor of one-half to Charles Bernhard, Great Neck, N. Y.

Application May 5, 1948, Serial No. 25,152

6 Claims. (Cl. 158—76)

1

This invention relates to combustion apparatus, and particularly to devices utilizing liquid fuel and known in the trade as oil burners.

While it is a fact that oil burners are on the market which are based on proper theories of fuel control and air supply, the difficulties encountered in installation and in servicing have resulted in a widespread situation of inefficiently operating burners being in constant use. In order that an oil burner may be properly installed, serviced and made to function with best efficiency, latitude in adapting the burner to installation in different makes of furnaces is necessary, and at the same time affording ready access by the serviceman to make inspections and adjustments. The air supply is a vital consideration in efficiency of an oil burner, and proper adjustment of the air supply while observing the character of flame being produced is featured in the present invention as an advance in the art. The invention further contemplates the provision of an oil burner readily adaptable to be installed for widely variant oil-flow requirements. Another object of the invention is to afford accessibility to the interior, and further objectives are to improve the means of retention of parts; simplicity of construction, assembly and use in general; and to obtain a highly efficient oil burner with minimum parts and adjustments.

Other objects and advantages of the present invention will appear to those skilled in the art to which it appertains as the description proceeds, both by direct recitation thereof and by implication from the context.

In the accompanying drawings in which like numerals of reference indicate similar parts throughout the several views;

Figure 1 is a vertical longitudinal section of a combustion apparatus in accordance with my invention;

Figures 2 and 3 are cross-sections on lines 2—2 and 3—3 respectively of Fig. 1;

Figure 4 is a view partially in elevation and partially in longitudinal section showing the air valve and its adjustable mounting;

Figure 5 is a perspective view of the air valve and associated parts partially withdrawn from the secondary air tube;

Figure 6 is a perspective view of the blast tube from which the service cover and the whirl chamber and cap are partially removed for illustrative advantage;

Figure 7 is a fragmentary longitudinal section of the blast tube at its end next the main housing and showing a modified attachment therebetween; and

Figure 8 is a cross-section on line 8—8 of Fig. 7.

In the specific embodiment of the invention illustrated in said drawings, the reference numeral 10 designates the main housing which provides for appropriate mounting and operation of a fan or blower 11 for creating the copious air supply required for apparatus of the character indicated. At the rear of this housing is an opening or hatch 12 for access to the interior, said hatch being normally closed with a cover (not shown) in operation of the burner. At the front of the housing, aligned with the rear opening or hatch 12 is a forward opening defined by a forwardly protruding hollow neck 13. Said neck constitutes a supporting means for a tubular jacket or blast tube 14 projecting forwardly from said neck and attached thereto. Coaxial to and within the blast tube 14 is an inner tube 15 considerably smaller and much closer to the end of the blast tube so as to provide an annular passage 16 between the inner tube and the blast tube for the primary air flow from the housing to the forward ends of said tubes. The interior of inner tube 15 in like manner constitutes a passage 17 for the secondary air flow from the housing to the forward end of said inner tube. At the forward end of the blast tube 14 is a hollow nose or air concentrator 18 the interior whereof constitutes a whirl chamber by virtue of a plurality of spiral vanes 19 therein. For installations where needed, further air concentration may be obtained by addition of a frusto-conical hollow nose extension or choke ring 20 secured on the forward part of said nose as by screws 21. Said hollow nose 18 and applied choke ring together are referred to herein as a cap.

Attention is directed to the fact that the forward end of inner tube 15 converges somewhat in its approach to and projection through hollow nose 18 whereby secondary air velocity at the end of said tube is increased, and said nose likewise has a converging relation to the nose thereby also increasing the primary air velocity from the nose. In those installations where the nose extension is employed the further constriction introduced thereby additionally increases the velocity of the primary air which adds velocity impetus to the stream of secondary air enveloped thereby. While nose 18 terminates rearwardly of the end of the inner tube, the extension 20 on the nose brings the effective outlet forwardly beyond the end of the inner tube. While convergence of the nose end of the air passages effects an increase in velocity of the air, it also tends to obstruct the air so that there is in

reality less air passing from the nose having the extension or choke ring 20 than passes from the nose with the extension omitted, thus obtaining a compromise of quantity and velocity of air. The burner with the nose extension obtaining increased velocity and less air volume is advantageously used on installations using oil at a rate of approximately two gallons per hour or less, whereas installations using more than two gallons per hour it is advantageous to decrease the air velocity and increase the air volume by omission of the nose extension. The burner thus constructed is adapted to more universal use on various installation requirements.

Coaxially within tube 15 is a fuel feed pipe 22 the forward end of which carries a usual or atomizing nozzle 23. The rear end of the coaxial feed pipe extends to the rear opening or hatch 12 of the housing and is there provided with an elbow 24 for connection, by pipe 25, to the usual fuel pump (not shown) or other source of fuel supply. Said feed pipe 22 is preferably fixed with respect to the housing, and by attachment to a spider bracket 26 is maintained coaxial within said tube 15. Said spider bracket has slidable engagement with the inner wall of said inner tube thereby permitting longitudinal adjustment of said tube without disturbing the position of the spider, feed pipe or nozzle. The spider also makes provision for support and retention of spark-forming electrodes 27 extending therefrom longitudinally of the feed pipe forwardly to a position next the fuel-ejecting forward end of the nozzle for igniting the fuel and instigating the flame. Electric cables or wires 28 connect to and extend rearwardly from said electrodes 27 and make exit through the housing 10 and hatch 12. Appropriate support for these cables may be provided, as required, by a tefoil or other bracket 29 mounted on the fuel feed pipe 22.

On the outside of inner tube 15 are secured a plurality of longitudinal fins 30 the outer edges of which have sliding contact with the inner surface of blast tube 14 thereby holding said tubes coaxial to each other but permitting the inner tube to be longitudinally adjusted with respect to the outer or blast tube. An adjusting bar 31 is secured to one of the fins 30, extending rearwardly therefrom in juxtaposition to a longitudinal slot 32 in the wall of the blast tube and has a screw 33 projecting from the bar through the slot movable in said slot for shifting the bar and inner tube lengthwise of the slot and tube. A wing nut 34 on the screw constitutes a convenient means for clamping the bar in place and thus holding the inner tube fixed in its adjusted position.

The rear end of inner tube 15 constitutes an annular seat 35 for engagement by a forwardly facing valve head 36 coaxial therewith and slideable upon fuel pipe 22. This valve head is constructed, arranged and retained to enable a wide range of adjustment of secondary air flow to be obtained for the inner tube, as the valve head may seat against the end of said tube or may be retracted varying distances to admit air up to the full capacity of the tube. As shown, the adjustment for said valve is by means of an arm 37 projecting radially therefrom in a location substantially diametrically opposite from the inner tube adjusting bar. This location is preferred so as to enable a workman to conveniently manipulate the inner tube adjustment and the valve head adjustment simultaneously with his two hands at diametrically opposite sides of the blast tube. An adjusting screw 38 extends rotatably

through said arm next the outer end of the arm with the screw paralleling the tube axis and the screw head at the rear side of the arm. The screw extends forwardly and threads into a circumferentially projecting leg 39 of an L-bracket the other leg of which is secured to one of the fins of the inner tube 15. A compression spring 40 surrounds the screw and applies resilient pressure to the radial arm 37 so as to keep the arm against the screw head in any adjusted position of the screw. Manipulation of said screw will accordingly locate the valve head in desired adjusted relation to the valve seat at the rear end of the inner tube and retain that adjustment irrespective of adjustment made of the location of the inner tube with respect to the outer tube and its nose.

A conveniently large hand hole 41 is made in the outer tube in vicinity of the valve head and its adjusting arm. As here shown, said hand hole is of elongated rectangular shape extending from approximately the valve to the rear end of said blast tube, and is closed in use of the combustion apparatus by a suitable cover 42.

A further feature of the invention resides in the convenient mounting of the blast tube upon the housing and assembly of the inner tube and valve therewith enabling ready removal of the several parts from the housing, as well as the simple return of or replacement of parts to their appointed places. In furtherance of this feature, the rear end of the blast tube where attaching to the housing neck 13, is longitudinally split as far as the hand hole so as to be diametrically expandable and contractable to fit the neck and to be releasable therefrom. In Figures 1, 2 and 3 the blast tube is constructed to be applied to the exterior surface of the neck and to be clamped thereon by a contracting clamp collar 43 of the general characterization of a hose clamp. In Figures 7 and 8, the rear split end of the blast tube is inserted within the hollow neck 13 and expanded and clamped by segmental arcuate clamp members 44 each of which has end portions 45 directed toward each other on a chordal line. The end portions, here referred to as a pair, of one clamp member are parallel to the pair of end portions of the other member. A screw 46 extends from one end portion of one pair to a corresponding end portion of the other pair and by virtue thereof the clamp members may be forced outward to clamp the blast tube against the inside wall of the housing neck.

I claim:

1. Combustion apparatus comprising a housing having a front opening, a blast tube projecting from said opening, an inner tube within said blast tube longitudinally adjustable therein, an adjustable valve head at an end of said inner tube, and adjusting means at opposite sides of the blast tube, one said adjusting means being attached in part to the blast tube and in part to the inner tube and the other adjusting means being carried in part by the inner tube and in part by the valve head.

2. Combustion apparatus comprising a housing having a front opening, a blast tube projecting from said opening, an inner tube within said blast tube longitudinally adjustable therein, longitudinal fins on said inner tube projecting radially therefrom and having guiding engagement with the blast tube, an adjustable valve head at an end of said inner tube, and two adjusting means, one for adjustment of the inner tube having connection with one fin and the blast tube,

and the other for adjustment of the valve head having connection with another fin and the valve head.

3. Combustion apparatus comprising a housing having a front opening, a blast tube projecting from said opening, an inner tube within said blast tube longitudinally adjustable therein, diametrically opposite longitudinal fins on said inner tube projecting radially therefrom, and having guiding engagement with the blast tube, an adjustable valve head at an end of said inner tube, and two adjusting means of which one is diametrically opposite the other and of which one is connected to one of said fins and the other is connected to a diametrically opposite fin and one of said adjusting means being connected with said blast tube and the other being connected to said valve head.

4. Combustion apparatus comprising a housing having a front opening, a blast tube projecting from said opening, an inner tube within said blast tube longitudinally adjustable therein, an adjustable valve head at an end of said inner tube, adjusting means for said valve head adjacent the same and wholly within said blast tube, said blast tube having a hand opening next said adjusting means, and a movable cover for said opening whereby access may be gained to said adjusting means.

5. Combustion apparatus comprising a housing having a front opening, a blast tube projecting from said opening, an inner tube within said blast tube longitudinally adjustable therein, an adjustable valve head at an end of said inner tube, adjusting means for said valve head adjacent the same and wholly within the said blast tube, said blast tube having a hand opening next said adjusting means, and a movable cover for

said opening whereby access may be gained to said adjusting means, and adjusting means at one side of the exterior of said blast tube for adjusting the position of the inner tube in the blast tube.

5 10 15 20

6. Combustion apparatus comprising a housing having a front opening, a blast tube projecting from said opening, an inner tube within said blast tube longitudinally adjustable therein, an adjustable valve head at an end of said inner tube, adjusting means for said valve head adjacent the same and within said blast tube, said blast tube having a hand opening next said adjusting means and a movable cover for said opening whereby access may be gained to said adjusting means, and adjusting means at the exterior of said blast tube diametrically on the opposite side of the blast tube from said hand opening for adjusting the position of the inner tube in the blast tube.
